US0D1107772S

(12) **United States Design Patent** (10) **Patent No.:** **US D1,107,772 S**
(45) **Date of Patent:** **** Dec. 30, 2025**

(54) **INDUSTRIAL ROBOT**

(71) Applicants: **KUKA Robotics Guangdong Co., Ltd.**, Foshan (CN); **Kuka Robotics Manufacturing China Co., Ltd.**, Shanghai (CN)

(72) Inventors: **Sivakumar Thangavelu**, Guangdong (CN); **Lien Lan**, Guangdong (CN); **Jie He**, Guangdong (CN)

(**) Term: **15 Years**

(21) Appl. No.: **35/520,812**

(22) Filed: **Feb. 4, 2024**

(80) **Hague Agreement Data**

Int. Filing Date: **Feb. 4, 2024**

Int. Reg. No.: **DM/236722**

Int. Reg. Date: **Feb. 4, 2024**

Int. Reg. Pub. Date: **May 10, 2024**

(51) **LOC (15) Cl.** **15-99**

(52) **U.S. Cl.**

USPC **D15/199**

CLAIM

The ornamental design for an industrial robot as shown and described.

DESCRIPTION

1. Industrial robot

1.1: Front

1.2: Back

1.3: Left

1.4: Right

1.5: Top

1.6: Bottom

1.7: Perspective view 1

1.8: Perspective view 2

1.9: Perspective view 3

1.10: Perspective view 4

1.11: Perspective view 5

1.12: Perspective view 6

1.13: Perspective view 7

1.14: Perspective view 8

The broken lines and areas enclosed by the broken lines depict portions of the industrial robot and form no part of the claimed design.

1 Claim, 14 Drawing Sheets
